UNITED STATES PATENT OFFICE.

LOUIS V. ARONSON, OF NEWARK, NEW JERSEY.

TOY PISTOL.

Application filed March 30, 1922. Serial No. 548,050.

To all whom it may concern:

Be it known that I, LOUIS V. ARONSON, a citizen of the United States, residing at Newark, in the county of Essex and State 5 of New Jersey, have invented certain new and useful Improvements in Toy Pistols, of which the following is a specification.

The invention relates to toys and has as an object the provision of a toy in the form 10 of a pistol which will produce a shower of sparks when the trigger is pressed; a further object is the provision of a toy of the nature referred to which will be capable of long operation without likelihood of getting 15 out of order. Further objects will appear from the following description.

Illustrative embodiments of the invention are shown in the accompanying drawings, in which—

20 Figure 1 is a side elevation with one-half of the casing removed;

Fig. 2 is a detail plan view of the working parts of the toy;

Fig. 3 is a detail perspective view of the 25 trigger and release dog;

Fig. 4 is a detail perspective view of the actuating gear;

Fig. 5 is a side elevation with half of the 30 case removed of a modified form of the invention;

Fig. 6 is a plan view of the operating parts of the mechanism of Figure 5, showing a portion of the casing in section, and drawn to an enlarged scale; and

35 Fig. 7 is a detail, exploded, perspective view of portions of the mechanism of Figure 5.

The form of the device shown in Figure 1 comprises a casing 10 which as shown simulates the form of an automatic pistol, the 40 two halves of the casing being adapted to be secured together by means of tongues not shown which may coact with the lugs 11, as by being bent thereabout. The operative 45 mechanism of the toy is preferably mounted upon a plate 12 which may be secured within the casing by means of tongues 13, 14 formed integral with the plate, passed through openings in the casing and being 50 clinched on the outside thereof in the manner shown in Figure 2.

To produce sparks, a friction wheel 15 having teeth preferably in the form of file teeth on the periphery thereof and having 55 a pinion wheel 16 secured rigidly to its side is shown as pivoted on plate 12. The fric-

tion wheel 15 is adapted to produce sparks by acting upon a pyrophoric element 17 held in a loop 18 formed of the material of plate 12 by bending the end of a tongue 19 into 60 the form of a loop.

To cause a revolution of the wheel 15 a rack in the form of a quadrant 20 is shown as pivoted at 21 upon the plate 12. In the form of the device shown in Figures 1, to 4, 65 inclusive, the quadrant 20 has a portion formed integral therewith and bent into a U shaped loop 22 having its extremity perforated as at 23 and adapted to act about the pivot of the quadrant 20.

To actuate the quadrant 20 a trigger 24 is shown as pivoted at 25 upon the plate 12. To provide two spaced openings for the pivot 25 the end of the trigger is doubled upon itself as at 26, Figure 3, the extremity 75 of the so bended portion being perforated as at 27 for the reception of the pivot pin 25. Coacting with the trigger 24 there is shown a dog 28 which may be pivoted to the trigger as by means of lugs 29 formed integral 80 with the dog and seated in openings 30 formed in the body of the trigger and in the end of a U shaped loop formed from the material of the trigger. The dog 28 as shown in Figure 1 coacts with the portion 85 22 of the quadrant 20. To press the dog toward the portion 22 a coiled spring is shown as seated upon the pivot 25 between the two portions of the end 26 of the trigger and having one extremity 31 seated in a slot 32 in 90 the end of the dog 28. The other extremity 33 of the spring is shown as seated in a notch 34 in a pressure lever 35 thereby anchoring the spring and pressing upwardly upon the end of the lever 35 to which it is 95 anchored. The lever 35 is utilized to place pressure upon the pyrophoric element 17 as clearly shown and is preferably pivoted upon the pin 25 which acts as a pivot for the trigger 24.

When the trigger 24 is drawn to the rear the dog 28 by virtue of its shoulder 36 draws the quadrant 20 slowly from its normal position wherein the flange 37 thereof seats against the portion 26 of the trigger acting 100 as a stop for movement, holding the same in a position of rest.

To free the quadrant from the dog 36, a projection shown in the form of a tongue 38 is provided upon the quadrant which 110 upon movement from normal, in due time, will impinge upon the portion 39 of the dog

and will cause the dog to move out of engagement with the portion 22 of the quadrant. When this takes place the quadrant will be suddenly returned to normal by action of a spring 40 which is coiled about the pivot 21 and has an end anchored behind the portion 22 of the quadrant. The end of the spring 40 is shown as also anchored in a notch of lever 35 and therefore assists in producing pressure upon the pyrophoric element 17.

The movement to the rear of trigger 24 increases the tension upon the spring 33. The movement from normal of the quadrant 15 increases pressure upon the spring 40 therefore in the beginning of the movements of the trigger and the quadrant the pressure upon the pyrophoric element is least at a time when no pressure is desired.

20 At the conclusion of the rearward movement of the trigger its pressure upon the spring 33 is greatest and also the pressure upon spring 40 is greatest thereby producing the maximum pressure upon element 17. 25 The maximum pressure upon spring 33 is maintained while the quadrant is returning to normal position, thereby preserving a considerable portion of the maximum pressure upon the element while the sparks are being produced.

To check the forward movement of the trigger, a lug 41 is shown as struck from the plate 12 and projecting in its forward path. In the form of the device shown in 35 Figures 5 and 6 and 7, the friction wheel 15' is shown as mounted upon a plate 12' which may be secured within the casing in the manner already described or by means of bolts 42. The friction wheel 12' is shown 40 as having rigidly secured thereto a pinion 16'.

To hold the pyrophoric element in this form of the device there is shown a flange 43 bent at right angles to the body of the plate 12' and a cylinder 44 secured to the flange having a slot 45 for reception of the pressure member 35'. The quadrant 20' is shown as pivoted upon the plate 12' and as adapted to be actuated by a dog 28' pivoted upon a trigger 24', the dog 28' coacting with a pin 22' upon the quadrant and adapted to be thrown out of engagement therewith by means of a pin 38'. The trigger 24' and the lever 35' are both mounted upon the pivot 25' as is the case in the form of the device first described.

In the form of the device of Figures 5, 6 and 7, the quadrant 20' is pressed to normal position by means of a spring 40' anchored 60 to a pin 41' and pressing against the stop member 37' of the quadrant. The spring 33' which places pressure upon the lever 35' is shown as coiled about the pin 25' and seated

between the doubled portions 43, 44 of the trigger and pressing against the inside of 65 the finger projection 45 of the trigger at 46. Therefore in this form of the device only the trigger spring provides a pressure upon the lever 35' which pressure is the greatest 70 during the return to normal of the quadrant 20' at the time when the greatest pressure upon the pyrophoric element is desired. The lever 35' as well as 35 of Figure 1 may be lifted against the pressure of the springs 75 anchored thereupon and a new pyrophoric element may be placed in the loop 18 when necessary.

The operation of the device shown in Figures 5, 6 and 7 is substantially identical with that shown in Figures 1 to 4 inclusive.

80 Minor changes may be made in the physical embodiment of the invention without departing from the spirit thereof.

I claim as my invention:—

1. A toy comprising, in combination, a 85 friction wheel, a pyrophoric element in contact therewith, means to press said element against said wheel, a spring to cause such pressure, a trigger adapted to cause actuation of said wheel, connections whereby movement of said trigger from normal increases the pressure exerted by said spring, and means to maintain the pressure of the spring at its maximum during movement of said wheel.

95 2. A toy comprising, in combination, a casing, a friction wheel mounted in said casing, a pinion secured to said wheel, a pyrophoric element in contact with said wheel, a pivotally mounted arcuate rack meshing with said pinion, resilient means pressing said rack toward normal position, a projection carried by said rack, a trigger, a dog carried by said trigger and coacting with said projection, means carried by said rack adapted to impinge against said dog to free it from the projection for release of the rack to permit its sudden return to normal whereby sparks will be produced by said friction wheel.

100 3. A toy comprising, in combination, a plate, a friction wheel mounted on said plate, a pyrophoric element in contact with said wheel, a pinion secured to said wheel, an arcuate rack pivoted upon said plate with its teeth in mesh with said pinion, a spring urging said rack toward normal position, a trigger pivoted on said plate, pressed to normal position, means whereby said trigger 115 when pressed may retract said rack and suddenly release the same, a stop for forward movement of said trigger, the pivoted extremity of said trigger acting as a stop for the rack in normal position.

LOUIS V. ARONSON.
